UNITED STATES PATENT OFFICE

AUGUST WEISLER, OF PERRYVILLE, MISSOURI, ASSIGNOR OF ONE-HALF TO F. J. HAGERLING, OF ST. LOUIS, MISSOURI

WRENCH

Application filed February 26, 1929. Serial No. 342,762.

This invention relates to the class of tools and pertains particularly to a wrench.

The primary object of this invention is to provide an improved wrench structure of the type embodying a fixed jaw and a shiftable jaw swingable relative thereto, an improved means being employed for controlling the movement of the shiftable jaw and for securing the same against accidental shifting in any adjusted position.

A further object of the invention is to provide a wrench of light but strong and durable construction, easy to manipulate and comparatively inexpensive to manufacture.

The invention will be best understood from a consideration of the following detailed description taken in connection with the accompanying drawing forming a part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a view partly in side elevation and partly in section of the wrench embodying the present invention;

Figure 2 is a plan view of the central portion of the wrench looking toward the shiftable jaw.

Referring to the drawing in detail wherein like numerals of reference indicate corresponding parts throughout the several views, the numerals 1 and 2 indicate the movable and fixed jaws respectively of the wrench embodying this invention, which jaws have respectively the shanks 3 and 4. The shank 4 forms one furcation of the bifurcated end of a handle 5, the other furcation being relatively short as shown and reduced at its end as indicated at 15.

The working face of the shiftable jaw 1

is preferably toothed or serrated as indicated at 6 while the opposed face of the fixed jaw is preferably smooth.

Between the shank 3 and jaw 1 of the shiftable jaw there is formed the passage 8 which receives in the inner end the post 9 which projects from and is formed integral with the inner face of the fixed jaw at the inner end thereof, as shown. This post 9 has an interiorly threaded bore 10 which passes longitudinally therethrough and through the jaw by which it is carried for the reception of an adjusting screw 11 which is passed through a washer 12 overlying the outer end of the passage 8 and resting against the back of the shiftable jaw, in the manner shown, the head 13 of the bolt bearing against the outer face of the washer.

At its rear end the shank portion 3 of the shiftable jaw is bifurcated as indicated at 14 and receives between the furcations the arm 15 which forms a part of the Y shaped end of the handle 5. The arm 15 is provided with the elongated transverse passage 16 for the reception of a pivot pin 17 which passes from one to the other of the furcations and thus pivotally secures the shiftable jaw and its shank to the shank of the fixed jaw.

Forwardly of the arm 15 the shanks 3 and 4 are provided with the opposed recesses 18 in each of which one end of a coil spring 19 is positioned as shown, this spring serving to normally force the jaws apart.

Secured to the back of the shank 3 of the shiftable jaw is a substantially Z-shaped latch 20 one leg thereof, as for example the leg 21, being pivotally secured to the shank by the screw 22 while the other leg, indicated by the numeral 23 is spaced a sufficient distance from the back of the jaw to engage over the head 13 of the bolt 11. From this it will be readily seen that while the bolt may be rotated between the thumb and forefinger without moving the latch 20, to bring the jaws together or move them apart as

desired, it is impossible to shift the movable jaw towards the fixed jaw without turning the screw unless the latch is swung to one side so that the portion 23 thereof will be removed from contact with the head 13 of the screw.

From the foregoing description it will be seen that the wrench structure embodying this invention is of such character that it may be inexpensively manufactured and assembled, is unlikely to get out of order due to the few movable parts of which it is made up and may be conveniently manipulated for use.

Having thus described my invention what I claim is:—

1. A wrench comprising a jaw, a shank carried by the jaw and a handle connected to the shank, a shiftable jaw, a shank carrying the shiftable jaw, a pivotal connection between said last shank and the first mentioned shank, said shiftable jaw having a passage therethrough from the front to the back face, a post rigid with the first mentioned jaw in position to extend into said passage, a headed screw member extended into said post through the outer end of said passage and having the head thereof acting upon the back of the shiftable jaw, and resilient means normally forcing said shiftable jaw outwardly against said screw head.

2. A wrench comprising a jaw, a shank carried by the jaw and a handle connected to the shank, a shiftable jaw, a shank carrying the shiftable jaw, a pivotal connection between said last shank and the first mentioned shank, said shiftable jaw having a passage therethrough from the front to the back face, a post rigid with the first mentioned jaw in position to extend into said passage, a headed screw member extended into said post through the outer end of said passage and having the head thereof acting upon the back of the shiftable jaw, resilient means normally forcing said shiftable jaw outwardly against said screw head, and a shiftable latch member carried by the shiftable jaw and engaging the screw head to prevent movement of the shiftable jaw on the post independently on the screw.

3. A wrench comprising a pair of jaw members each having a shank, a handle rigid with one of said shanks, means providing a loose pivotal connection between the other shank and the handle whereby movement of the said other shank and the associate jaw is permitted toward or away from the adjacent jaw and shank, a rigid post formed integral with the fixed jaw forwardly of the pivotal connection between the jaws, said shiftable jaw having a passage therethrough for loosely receiving the post and said post having a threaded passage extending longitudinally therethrough, a control screw extending through the passage of the shiftable

jaw and threadably engaged in said post and having a head overlying the shiftable jaw adjacent the passage therethrough, an oscillatable latch carried by the shiftable jaw and adapted to engage said screw head to prevent movement of the shiftable jaw toward the fixed jaw, and a spring member between the post and the pivot point of the jaws normally urging the jaws apart.

In testimony whereof I hereunto affix my signature.

AUGUST WEISLER.
